J. St. JOHN.
Grain Hulling Machine.

No. 233,381.

Patented Oct. 19, 1880.

INVENTOR:

Joseph St. John.

UNITED STATES PATENT OFFICE.

JOSEPH ST. JOHN, OF PENN YAN, NEW YORK.

GRAIN-HULLING MACHINE.

SPECIFICATION forming part of Letters Patent No. 233,381, dated October 19, 1880.

Application filed February 18, 1880.

To all whom it may concern:

Be it known that I, JOSEPH St. JOHN, of Penn Yan, in the county of Yates and State of New York, have invented a new and useful 5 Improvement in Grain Cleaning, Hulling, and Separating Machines, of which the following is a specification.

My invention relates to improvements in grain cleaning, hulling, and separating machines in which there is a stationary hulling-stone, provided with a draft-opening and fan-connection between the eye and skirt of the stone to draw the dust from the grain contained between the stones, and a running-stone, concaved in the center and having a plain hulling-surface extending inwardly from the skirt to meet the concaved portion of the stone; and the objects of my invention are, first, to remove dust and dirt from the outside 15 of the grain before it is hulled; and, second, to hull the grain after it is cleaned and before it leaves the stones.

In the accompanying drawing the figure is a longitudinal vertical section of the machine 25 constituting my invention.

A is the frame-work that supports the several parts of the machine. It may be made of wood or iron, or a part of each, the upper part made to receive the running-stone F and 30 support the upper stone, E, and the sieves and fan and fan-spout are placed between its legs.

B is the spindle that supports and drives the running-stone. The pivot, at its lower 35 end, is provided with a step, by which it is held in position, and with which the spindle may be raised or lowered at will. The step is attached to the under side of the top of the frame. The upper end is held by braces fastened to the top of the frame, and at the upper 40 end the driving-pulley is applied and fastened.

C is the hopper that conducts the grain into the eye of the upper stone. It may be made in any ordinary manner.

D is the curb surrounding the stone. It 45 may be made of wood or metal, as preferred.

E is the upper stone. It may be made of any kind of stone now in use. It is made circular in form, and the under side is flat and 50 with or without furrows, as preferred. It is held in position by supporters, that will allow

its lower face to be adjusted parallel to the upper face of the lower stone. The upper surface may be made to suit the wishes of the maker or user. It has a hole in the center for 55 the spindle B to pass through, also for the grain to pass down through, also a hole near the periphery for dust to pass out, as shown in the figure.

F is the under stone. It should be made of 60 the same material as the upper one and about the same diameter. It is fastened to the spindle B. The upper surface is divided into two parts. The part at the edge is flat and like an annular rim, and it may be roughened with 65 a pick, and must be dressed to correspond with the upper stone. That part within the annular rim is made concave, to hold within proper limits any required amount of grain, so that the motion of the stone will impart motion to the grain, thereby rubbing one grain against another and against the upper stone, thus liberating the dusty substance before 70 the grain passes over the annular rim and is hulled.

G is the fan and its case and spout. The spout extends from within the hole near the edge of the upper stone to any desirable place to discharge the dust. The fan may be made as large as desired, and must be driven fast 75 enough to draw the liberated dust from the concavity between the stones.

H is a series of sieves used to separate the hulls from the grain. They may be made of any size of wire-gauze to suit the various kinds 85 of grain to be hulled, or of various sizes to separate, when it is desirable to separate, coarse from the finer portions of grain. The hulls pass off the upper sieve, the grain passes through it. All the sieves let the hulled grain 90 through, and when any unhulled grains pass through the upper sieve they are carried off by the lower sieves and discharged into the box or spout I, to be conveyed again into the hulling-stones. The hulled grain falls down 95 through the spout J at the bottom board beneath the lowest sieve into the spout M.

L is the fan that blows away the dust that may pass with the grain down through the sieves. It is provided with the ordinary fan-case and band-wheel to give it the proper motion.

M is a spout extending from the fan-case, as shown in the figure. It conveys the wind from the fan to the grain while it is falling through it from the spout K. This spout K 5 receives and conducts the grain down into the spout M. There is also a spout, N, to discharge the cleaned grain into a receptacle or conveyer to take it to be ground.

O is a cant-board placed across the spout 10 M for the grain to fall upon, to impede its motion and scatter it so that the wind may more effectually clean it, and in connection with it are guides, as shown in the figure, that direct the wind to the top and bottom of the spout 15 M, to intensify it while acting upon the grain and allow it to pass on beyond the grain with less force while carrying the dust out of the end of the spout.

P is a knocker made to impinge against the 20 bottom board of the sieves to prevent the sieves clogging. It is composed of a lever bent so as to strike against the bottom board. It has a notch in the upper edge for the cam 25 Q to actuate it with, and a fulcrum at the other

end to hold it in place, and is provided with a 25 spring underneath it, all as represented in the figure.

Q is the cam that actuates the knocker. It is placed on a shaft underneath the sieves, and is driven by a band-wheel that will give 30 it but slow motion.

Having thus fully described my invention, what I claim as new, and desire to secure by Letters Patent, is—

The upper stationary hulling-stone, provided with a draft-opening and fan-connection between the eye and skirt, in combination with the runner, concaved in the center and having a plain hulling-surface extending inwardly from the skirt to meet the concaved 40 portion, whereby the dust liberated by the centrifugal action of the runner may be drawn off before the grain is subjected to the hulling action of the stones at the skirt, substantially as described.
